CHILD'S SPACE SHIP TOY

Howard E. Grant, Farmingdale, N.Y., assignor to Automatic Concessions Corporation, Westbury, N.Y., a corporation of New York

Filed Jan. 24, 1961, Ser. No. 63,666

Term of patent 14 years

(Cl. D34—15)

FIGURE 1 is a side perspective view of a child's space ship toy, showing my new design, looking into the interior of the rocket and towards the control panel therein;

FIGURE 2 is a perspective view of the side opposite that of FIGURE 1;

FIGURE 3 is a side perspective view thereof, also looking into the interior of the rocket and towards the seat therein;

FIGURE 4 is a top plan view thereof; and

FIGURE 5 is a horizontal cross section through FIGURE 1 above the radar screen shown therein.

The dominant features of my design are shown in full lines.

I claim:

The ornamental design for a child's space ship toy, as shown and described.
